Patented June 7, 1921.

FIG. 1.

FIG. 2

Inventor
William T. Kolva

By George H. Snyder
Attorney

UNITED STATES PATENT OFFICE.

WILLIAM T. KOLVA, OF VINELAND, NEW JERSEY.

GAS-DEFLECTOR.

1,381,092.

Specification of Letters Patent. Patented June 7, 1921.

Application filed May 1, 1920. Serial No. 378,048.

To all whom it may concern:

Be it known that I, WILLIAM T. KOLVA, a citizen of the United States, residing at Vineland, in the county of Cumberland and State of New Jersey, have invented certain new and useful Improvements in Gas-Deflectors, of which the following is a specification.

This invention relates to gas burner deflectors and it consists in the novel features hereinafter described and claimed.

An object of the invention is to provide a deflector in the form of an attachment adapted to be applied to a gas burner for the purpose of concentrating the flame therefrom in order that the flame may be more directly applied to the central portion of the under side of a cooking utensil which is placed over the burner.

20 A further object of the invention is to provide in a deflector of the character stated means whereby air may be led to the flame at the point of concentration thereof and at the inner and outer sides of the flame whereby 25 sufficient oxygen is supplied to the flame at the area of concentration to produce a flame of maximum degree of heat temperature.

With these objects in view the deflector comprises a cone-shaped plate or disk provided at its edge with lugs and at its inner side with radially disposed ribs. The plate is provided at its center and at the apex of the cone with an opening which is stellaform in shape and the said ribs are disposed between the outer ends of the points of the said opening.

In the accompanying drawing:

Figure 1 is a transverse sectional view of a burner with the deflector applied;

40 Fig. 2 is a bottom or under plan view of the deflector.

As illustrated in the accompanying drawing the flame deflector and concentrator comprises a circular disk or plate 1 which is in the general shape of a flattened cone. The plate is provided at its center and at the apex of the cone with a stellaform opening 2 and the plate is provided at its peripheral edge with spaced lugs 3 which are adapted

to rest upon the top surface of a gas burner, 50 as shown in Fig. 1 of the drawing, when the plate is applied to the burner and when the diameter of the burner is sufficiently great to receive the lugs thereon.

The plate 1 is provided at its under side 55 with radially disposed ribs 4 which extend inwardly from the periphery of the plate and lie in lines midway between the outer points of the stellaform opening 2 and which at their inner ends terminate in circular alinement with the outer ends of the outer points of the said opening. When the plate is applied to a gas burner which is convexed at its upper surface the ribs 4 will engage the upper surface of the burner and 60 hold the under surface of the plate 1 spaced from the burner whereby air may pass from the exterior between the burner and the plate and feed the flame which is concentrated and 65 burning at the stellaform opening in the 70 plate.

From the foregoing description taken in conjunction with the accompanying drawing it will be seen that a flame concentrator and deflector of simple and durable form is provided and when applied to the burner of a gas stove will effect a saving of the gas in that the flame will be concentrated under the center of the bottom of a utensil which is placed over the burner, and the flame is fed 75 with oxygen which will assure the complete consumption of the gas while in flame and at the stellaform opening of the plate attachment. The stellaform configuration of the opening 2 gives the marginal edges of 80 the flame maximum dimensions and hence a large flame is produced in minimum area.

Having described the invention, what is claimed is:

A burner attachment comprising a cone-shaped plate provided at its center and at the apex of the cone with a stellaform opening and provided at its under side with radially disposed ribs which are located between the outer ends of the points of the opening. 90

95 In testimony whereof I affix my signature.

WILLIAM T. KOLVA.
